UNITED STATES PATENT OFFICE.

TORVAL N. ULEVOG, OF EARL GREY, SASKATCHEWAN, CANADA.

PLOW-LIFT.

1,279,792.

Specification of Letters Patent. Patented Sept. 24, 1918.

Application filed November 1, 1917. Serial No. 199,781.

To all whom it may concern:

Be it known that I, TORVAL N. ULEVOG, a citizen of the Dominion of Canada, and a resident of Earl Grey, in the Province of 5 Saskatchewan and Dominion of Canada, have invented certain new and useful Improvements in Plow-Lifts, of which the following is a specification.

The present invention relates to plows, 10 and has particular reference to that type adapted to be engine drawn and used in gangs.

An object of the present invention is to provide means for automatically lifting the 15 plows and holding the same above the ground surface when the plows are not in use, and for automatically dropping the plows to the desired distance in the earth when the plows are in use; and to provide 20 means for engaging or measuring the depth of the plows relatively to a prior formed furrow, or furrow turned up by an advanced plow.

The invention also has for an object the 25 provision of a peculiar mounting for a wheel upon a plow beam for supporting the latter by the wheel, and also for raising and lowering the beam by the vertical movement of the wheel when rolled into and out of furrow; and to provide a wheel mounting or 30 connection comprising relatively few parts and which are automatically moved relatively to one another incident to the change in the angle of the plow beam relatively to a 35 draft frame employed.

The above, and various other objects and 40 advantages of this invention will be in part described, and in part understood, from the following detailed description of the present preferred embodiment, the same being 45 illustrated in the accompanying drawings, wherein—

Figure 1 is a side elevation of a traction or engine drawn plow having the improvements 45 of this invention applied thereto and showing the plow in operation with the point in a furrow.

Fig. 2 is a similar view disclosing the parts 50 adjusted in position when the supporting and left wheel is raised out of a furrow.

Fig. 3 is a top plan view of a gang plow frame having the attachment of this invention applied thereto.

Fig. 4 is a front elevation of the same.

55 Fig. 5 is a detail front elevation of a supporting and lifting wheel arm.

Fig. 6 is a fragmentary enlarged side elevation of the lifting wheel arm, the supporting beam for the arm, and the operating lever connected and carried by the arm. 60

Fig. 7 is a vertical section through the same taken substantially on the plane indicated by the line 7—7 in Fig. 6.

Fig. 8 is a top plan view of the guide employed for supporting the wheel arm. 65

Referring to the accompanying drawings, the invention is disclosed as applied to a gang plow of the engine drawn type, and wherein 10 designates a draft frame of any suitable construction provided with a coupler or clevis 11 to which is pivotally connected a pair of plow beams 12. The beams 12 are held in spaced apart relation by bosses 13 arranged between the forward and rear end portions of the beams. The beams 12 70 are provided at their rear ends with plow points 14 of usual construction.

One of the beams 12, preferably the beam on the outer side, or the side toward which the wheel of the adjacent plow is formed, is 80 provided with a vertical guide or way 15 which, as shown in detail in Fig. 8, may comprise a casting having a plate or body portion adapted to be bolted or otherwise suitably secured against the outer face of the 85 beam 12 for supporting the guide body 15 rigidly upon the beam. The guide is provided with outstanding substantially parallel flanges overturned at their outer edge portions and extending toward each other to 90 form an undercut or key slot in the guide. Slidably mounted in the guide 15 is one end of an arm 16, which end is relatively straight and adapted for vertical movement in the 95 guide. The arm 16 is bowed upwardly and has its other end relatively long and projecting down toward the ground in laterally spaced relation from the plane of the beam 12. The longer end of the arm 16 has pivoted thereto a combined supporting and lifting wheel 17, and is provided with a base 18 forming with the lower end of the arm 16 a fork within which the wheel 17 is mounted.

The wheel 17 and its arm 16 are adapted to rise and fall as the wheel 17 passes over 100 undulations in the ground.

The inner end of the arm 16 is provided with a pivot 19, shown in Fig. 7 in the form of a bolt, and upon which is pivotally mounted between its ends a lever 20. One 110 end of the lever 20, the rear end thereof, is connected by a link 21 to the rear end of the

adjacent plow beam 12, while the outer or forward end of the lever 20 is connected by a rod 22 to a depending bracket 23 carried upon the rear end of the draft frame 10. 5 The connecting rod 22 is of such length that when the plow is drawn over the upper surface of the earth with the supporting and lifting wheel 17 traveling substantially in the same horizontal plane as that of the 10 carrier wheels of the draft frame 10, the lifting lever will be swung upon the link 21 into a position to force the arm 16 downwardly and thus raise the beam 12, and the plow points 14 connected thereto. The lever 15 20 and the connecting rod 22 are of such relative length that the plow points 14 are elevated a considerable distance above the surface of the ground when the combined lifting and supporting wheel 17 is traveling 20 thereover. As shown in Fig. 1, however, as soon as the lifting wheel 17 drops into a furrow, the angle between the draft frame 10 and the plow beam 12 is lessened and approaches a straight angle with the result 25 that the linear distance between the pivotal point of the lever 20 upon the arm 16 and the forward end of the connecting rod upon the draft frame 10 is lessened and the forward end of the lever 20 is raised and the 30 beams 12 are lowered. The connecting rod 22 is of a predetermined length in order to drop the plow points 14 into the ground the desired distance. The arm 16 is so curved that the ends thereof substantially bridge 35 the space between the furrow formed by the adjacent plow 14 and the prior formed furrow. The supporting wheel 17 is adapted to travel in the prior formed furrow and to thus adjust, automatically, the position 40 of the plow points 14 in the ground to form the new furrows.

It is of course understood that various changes and modifications may be made in the details of construction and design of the 45 above specifically described parts of this invention without departing from the spirit thereof, such changes and modifications being restricted only by the scope of the following claims:

50 I claim:

1. The combination with a draft frame, a plow beam pivoted thereto, and a plow point carried by the plow beam, of an arm slidably mounted for substantially vertical 55 movement upon the plow beam, a supporting wheel connected to the lower end of the arm adapted to travel over the ground, a connection between said arm and the plow beam for supporting the latter on the arm, 60 and means between said connection and the draft frame for automatically adjusting

the connection to raise and lower the plow beam upon the change in the angular relation between the draft frame and the plow beam.

65

2. The combination with a draft frame, a plow beam pivoted to the frame, and a plow point carried upon the beam, of an arm vertically slidable upon the beam, a wheel mounted on the lower end of the arm adapted to travel over the ground, a lever pivoted intermediate its ends upon said arm, a link connecting one end of the lever to the plow beam, and a connecting rod attached to the opposite end of the lever and to the draft frame for swinging the lever upon variation in the angular relation between the draft frame and the plow beam to move the arm vertically upon the latter and raise and lower the plow point.

70

3. The combination with a draft frame, a plow being pivotally connected to the draft frame, and a plow point carried upon the plow beam, of a vertical guide on the plow beam, an arm slidably mounted in the guide, a supporting wheel in the lower end of said arm adapted to travel over the surface of the ground, a lever pivotally mounted intermediate its ends upon said arm, a link connecting one end of the lever to the plow beam, a bracket depending from the rear end of the draft frame, and a connecting rod between said bracket and the other end of said lever.

75

4. The combination with a draft frame, a plow beam pivotally connected to the draft frame, and a plow point carried upon the plow beam, of a vertical guide mounted on the plow beam, an arm slidably in said guide, a supporting wheel on the lower end of the arm adapted to travel over the surface of the ground, a lever pivotally mounted intermediate its ends upon said arm, a link connecting the rear end of the lever to the rear end of the plow beam, a bracket depending from the rear end of the draft frame, and a connecting rod pivotally connected at opposite ends respectively to said bracket and to the other end of said lever.

80

5. The combination with a draft frame, a plow beam pivotally connected to the draft frame, and a plow point carried upon the plow beam, of a vertical guide mounted on said beam, an arm slidably mounted in the guide, a wheel carried upon the lower end of said arm adapted to traverse the ground surface, a lever pivotally mounted on said arm, a link connecting one end of the lever to said beam, a bracket depending from said draft frame, and a connecting rod between the bracket and the other end of said lever.
